United States Patent Office

Des. 191,741
Patented Nov. 14, 1961

191,741

CHAIR

Sheldon M. Rutter, Miami, Fla., assignor to Birmingham
Ornamental Iron Company, Inc., Birmingham, Ala., a corporation of Alabama

Filed Oct. 28, 1960, Ser. No. 62,657

Term of patent 14 years

(Cl. D15—1)

FIG. 1 is a side elevational view of a chair showing my new design, the opposite side being identical in appearance to the side shown;

FIG. 2 is a front view thereof; and

FIG. 3 is a top plan view thereof.

I claim:

The ornamental design for a chair, substantially as shown and described.
